UNITED STATES PATENT OFFICE.

JAMES E. WOODWARD, OF WATERTOWN, MASSACHUSETTS, ASSIGNOR TO HENRI A. SEVIGNE, OF WINTHROP, MASSACHUSETTS.

COMBINED PRIMER AND HUMIDIFIER FOR INTERNAL-COMBUSTION ENGINES.

Application filed June 13, 1921. Serial No. 477,261.

To all whom it may concern:

Be it known that I, JAMES E. WOODWARD, a citizen of the United States, and resident of Watertown, in the county of Middlesex 5 and State of Massachusetts, have invented certain new and useful Improvements in Combined Primers and Humidifiers for Internal-Combustion Engines, of which the following is a specification.

10 This invention relates to internal combustion engines and has particular reference to means for facilitating the economic use of a motor vehicle such as a truck by enabling the user to prime the motor with gasoline at such times as when starting and to then effect the introduction of water vapor when desired, which introduction of vapor will then continue automatically for any required length of time.

15 20 Of the accompanying drawings which illustrate practical embodiments of my invention:

Figure 1 conventionally illustrates sufficient parts of a motor vehicle, including my 25 improved attachments and connections, to enable the invention to be understood.

Figure 2 is a plan view of the vapor valve and trap.

Figure 3 represents a section on line 3—3 30 of Figure 2.

Figure 4 is a plan view of the lower or trap member and the valve seat.

Figure 5 represents a longitudinal section 35 of the primer pump.

Figure 6 represents a section on line 6—6 40 of Figure 5.

Figure 7 represents a section on line 7—7 45 of Figure 5.

Figure 8 is a view from the right of 50 Figure 5.

Similar reference characters indicate similar parts in all of the views.

The radiator 12, dash board 13, engine or motor 14, intake manifold 15, carburetor 45 55 16 accelerator rod 17 and the pedal 18 and link and lever connections 19, 20, therefor, may be of any well known or preferred construction.

Secured to the dashboard 13 in conveniently accessible position is a gasoline primer pump the outer casing or cylinder of which is indicated at 21 (Figs. 1, 5 and 6). The cylinder 21 has an end cap 22 formed with a flange portion 23 having holes (Fig. 7) 55 through which suitable screws or bolts pass

into the dashboard. A central nipple 24 of the cap 22 has an angular recess 25 the purpose of which will be presently described.

The other end of the cylinder 21 has 60 branch nipples 26, 27. The nipple 26 is coupled to a pipe 28 and its port 29 is normally closed by an inwardly-seating spring-actuated ball valve 30. The nipple 27 is coupled to a pipe 31 and its outer port 32 65 is normally closed by an outwardly-seating spring-actuated ball valve 33.

The cylinder 21, at an intermediate point of its length has ported nipples 34, 35, (Figs. 6 and 8), the nipple 35 being coupled to a 70 pipe 37 (Figs. 1 and 8) and the nipple 34 being coupled to a pipe 36.

Mounted to be reciprocated in the cylinder 21 is a piston head 38 having a suitably packed extension 39, the stem or rod 40 of 75 the head 38 passing through the end cap 22 and having a knob or handle 41 fixed to its outer end. Said piston rod 40 also has a pin or finger 42 (Fig. 7) normally lying in the recess 25 when the piston and its rod 80 are in the inward position shown in Figures 1 and 5, a spring 43 being located in position to normally hold the piston and rod at the inner end of the stroke thereof.

The piston is capable of being rotated as 85 well as drawn back by the knob 41, and the portion 38 of the piston is formed with a transverse port 44 adapted to register with the ports in the nipples 34, 35, when in the position shown in Figures 5 and 6. By 90 partially rotating the piston within the limits prescribed by the pin 42 in recess 25, said piston is caused to act as a valve to open or close the passageway through the nipples 34, 35, and the pipes 36, 37, for the 95 purposes described hereinafter.

Referring now to Figures 2, 3 and 4 in connection with Figure 1, the device for controlling the passage of water vapor to the intake manifold of the motor comprises 100 a lower or base member 45 which as illustrated is secured to the dashboard in any suitable manner, said member having a chamber 46 with a drip outlet 47 and a threaded inlet 48 for one end of a pipe 49 105 the other end of which is connected with the radiator 12 at a point of the latter where water vapor accumulates when the radiator is warm. Secured above the chamber 48 is 110 a plate 50 having segmental openings 51 and

a pin 52. The plate 50 forms a valve seat for the disk valve 53 having segmental openings 54 and an edge recess 55 to cooperate with the fixed pin 52 in limiting the rotary movement of the disk valve in either direction.

The disk valve is secured to the lower end of a stem 56 rotatably mounted in the cap member 57 which is secured to the base member 45 by suitable screws, the said valve and stem being acted upon by a spring 58 to hold the valve closely on the seat 50.

Secured to the upper end of the valve stem is an arm 59 to the outer end of which is connected one end of a link 60 the other end of the link being connected by a coupling 61 with the accelerator rod 17. Preferably, to allow for convenient assemblage and operation, the ends of the link 60 have ball and socket connections with the valve arm 59 and the coupling 61 as indicated at 62 in Figure 2.

The cap member 57 is provided with a threaded opening 63 (Figs. 2 and 3) to which the lower end of pipe 36 is connected (Fig. 1).

The gasoline supply pipe 64 leading to the carburetor 16 has a T-coupling 65 to which the lower end of pipe 31 is connected. The pipes 28 and 37 lead to any suitable portions of the intake manifold to supply the priming gasoline and water vapor thereto.

When in use, assuming that the devices and connections are installed in a motor truck or other motor-driven vehicle, the operator will first grasp the knob or handle 41 and actuate the pump so as to alternately draw gasoline through the pipe 31 from the supply pipe 64 and force it through pipe 28 to the intake manifold 15 so as to prime the motor and start it. Then, as soon as the motor is warm enough the operator leaves the piston in the position to which the spring 43 tends to move it (see Fig. 5) but turns the rod or stem 40 to ensure its pin 42 being in the position shown in Figure 7 which will ensure the existence of a free passageway through the nipples 34, 50 35, and the piston head.

After this the operation of the accelerator rod, in the usual manner, by the pedal 18, will, through the link 60, cause more or less opening of the valve consisting, in this embodiment of the invention, in the disk valve

53 and its seat 50, the openings in the valve ad seat being so formed (Fig. 4) that the further the pedal is depressed the greater will be the amount of registration of said openings. When the valve disk is turned more or less as explained, more or less water vapor passes from the radiator through pipe 49 into the trap chamber 46, past the disk valve, through pipe 36, and then through the now open port 44 of the piston head, and the pipe 37 to the manifold 15.

If there should be any overflow of water from the radiator into pipe 49, it will be trapped in the chamber 46 and escape through drip outlet 47.

It will now be understood that the pumping device substantially as illustrated constitutes, when properly connected by piping, a single member for operation to both effect priming of the motor and to open or close the connections for introducing water vapor to the manifold 15. This is due to the transverse port 44 in the piston member 38 and the nipples 34, 35, whereby the operator may either reciprocate the piston member to effect the pumping action described, or turn it without reciprocating it so as to open or close the passageway through the pipes 36, 37. Therefore I do not limit myself to the specific structure of valve shown in Figures 2, 3, and 4 as any mechanically equivalent valve device operated in synchronism with the usual butterfly valve which is controlled by the accelerator rod may be substituted for the valve shown without departing from my invention.

I do not claim herein the vapor control valve illustrated in Figures 2, 3 and 4, as the same forms the subject matter of claims in my application filed September 13, 1922, Serial No. 588,002.

Having now described my invention, I claim:

The combination with an internal combustion engine of a pump having a piston member provided with a transverse port, and connections to enable said pump to either effect priming of the engine or for said piston member to open or close a passageway for the introduction of vapor to said engine.

In testimony whereof I have affixed my signature.

JAMES E. WOODWARD.
